UNITED STATES PATENT OFFICE.

WILLIAM A. NETTLETON AND CHARLES F. LITTLEJOHN, OF BRIDGEPORT,
CONNECTICUT; SAID LITTLEJOHN ASSIGNOR TO SAID NETTLETON.

MACHINE FOR COVERING CORSET-STAYS.

SPECIFICATION forming part of Letters Patent No. 340,347, dated April 20, 1886.

Application filed January 2, 1886. Serial No. 187,505. (No model.)

To all whom it may concern:

Be it known that we, WILLIAM A. NETTLETON and CHARLES F. LITTLEJOHN, citizens of the United States, residing at Bridgeport, in the county of Fairfield and State of Connecticut, have invented certain new and useful Improvements in Machines for Covering Corset-Stays; and we do hereby declare the following to be a full, clear, and exact description of the invention, such as will enable others skilled in the art to which it appertains to make and use the same.

Our invention has for its object the production of mechanism for covering separate trimmed corset-steels or dress-stays with cloth, paper, or any suitable material.

Heretofore it has been common to cover a continuous flat spring or strip of wire with paper or cloth, which strip was then cut into suitable lengths for corset-stays. This method, however, required that the ends of the stays should be finished in some manner or capped.

We are not aware that any machine has been devised that will automatically cover stays already cut into proper lengths, that will leave any desired length of cloth between the stays, and will cut the cloth at any desired place after the stays have been covered. With these ends in view we have devised the novel machine of which the following description, in connection with the accompanying drawings, is a specification.

Similar numbers denote the same parts in all the figures of the drawings.

Figure 1 is a side elevation of the entire machine, a portion of the frame-work being broken away at one end to show the cutting device. Fig. 2 is a plan view on an enlarged scale, illustrating the essential features of our invention, the weight being removed from the magazine. Fig. 3 is a vertical section of a portion of the bed and the cross-slide on the line $x x$ in Fig. 2. Fig. 4 is a vertical cross-section on the line $y y$ in Fig. 2, the parts being in the position they occupy at the instant that a stay is expelled, the weight being removed. Fig. 5 is a similar cross-section showing the retracted position of the cross-slide and fingers—that is, at the instant a forward movement to expel another stay is about to begin. Fig. 6 is a detail view of the rollers which form the

strip to receive the stay. Fig. 7 is a view corresponding with Fig. 5, with the exception that certain parts are removed, and illustrating a modified form in which spring-fingers are used, which are attached to the front of the cross-slide, not being recessed into either the carrying-plate or the cross-slide; and Fig. 8 is a cross-section of the modified form on the line $z z$ in Fig. 7.

1 is the frame-work, 2 the bed, and 3 an extension or carrying plate secured in any suitable manner to the bed or frame-work of the machine.

The strip of cloth or paper with which the stays are covered is carried by a roller, 4, journaled in the frame-work.

5 indicates the strip of cloth. As it is drawn from roller 4, the cloth passes over the surface of the pasting-roller 6.

7 is a trough or receptacle, of any suitable construction, for paste or glue.

8 is a scraper, which acts to keep the surface of the pasting-roller in proper condition; 9, an oil or gas stove under the trough to keep the paste heated. After leaving the pasting-roller the strip passes over a roller, 10, which turns it, leaving the pasted side up. The strip next passes between forming-rollers 11 and 12, which form it (i. e., into trough shape) to receive the stay.

The parts just described may be of any suitable construction.

The style of machine illustrated is found in practice to work in a perfectly satisfactory manner.

13 is a magazine secured in any suitable manner to the bed or frame-work, in which stays are placed, they being held flat and forced down into the path of the fingers by a weight, 14.

15 indicates a cross-slide moving in ways 16 in the carrying-plate.

17 indicates fingers, which are ordinarily rigidly secured to the cross-slide and reciprocate in grooves 18 in the carrying-plate. Any number of fingers may be used. We have illustrated three in the drawings, and preferably use that number. These fingers project forward from the cross-slide and pass into holes 19 in the base of the magazine at each reciprocation.

20 is the floor of the magazine, and 21 a slot through the magazine at the back, extending its entire length.

It will be noticed in Fig. 5 that the tops of 5 the fingers project above the floor of the magazine just the height of one stay. It will also be noticed that slot 21 just permits the fingers to pass through it, carrying one stay before them. The retracted position of the fingers is shown 10 in Fig. 5, a stay having been pressed down upon the floor of the magazine ready to be forced out by the fingers. Fig. 4 shows the fingers at their extreme forward position, the stay having just been thrown out.

15 Turning now to the left of the machine, 22 and 23 represent drawing-rollers, whose shafts 24 and 25 are journaled in the frame-work.

20 26 and 27 are two rollers at the extreme left of the machine, which serve as cutting-rollers, and may also serve as drawing-rollers, their shafts also being journaled in the frame-work.

25 30 is the driving-pulley, which we preferably attach to shaft 28.

30 31 is a gear on shaft 28, 32 is a gear on shaft 24, and 33 an intermediate gear, which communicates the motion of gear 31 to 32.

35 The reciprocating motion of the cross-slide may be imparted in any suitable manner. We have, however, provided a crank, 34, at the 40 end of shaft 24, which carries a connecting-rod, 35, the other end of which is pivoted to one arm of a bell-crank lever, 36. This lever is journaled upon a stud, 37, which is secured 45 in the carrying-plate and projects upward through a slot, 38, in the cross-slide. The other arm of the bell-crank lever is provided with a slot, 39, which is engaged by a pin, 40, carried by the cross-slide. It will thus be seen that each revolution of shaft 24 imparts a forward and backward movement to the cross-slide. After leaving the forming or folding 50 rollers 11 and 12 the strip of cloth or paper passes forward, and is ready to receive a stay.

45 Each reciprocation of the fingers forces a stay out from the magazine, carries it forward, and deposits it in the center of the strip as it passes beneath. If preferred, the strip, after leaving the forming-rollers, may be passed through 55 a trough, 41, the stay being forced out and into the strip while it is in the trough. The drawing-rollers act continuously and draw the strip forward with the stays within it. The stays and strip then pass into the folder 42, which folds first one side of the strip, then the other, down upon the stay. The lower fold of course adheres firmly to the stay and the upper fold adheres to that. Both folds are pressed firmly into position as they pass through the 60 drawing-rollers. If preferred, one of the drawing-rollers, likewise one of the cutting-rollers, may be carried by spring-boxes. As this is a well-known feature of construction, however, we have not deemed it necessary to illustrate 65 it. After leaving the drawing-rollers the strip, with a stay inclosed within it, passes between the cutting-rollers, one of which is pro-

vided with a knife or cutter, 43, the other with a slight groove, 44. It will of course be understood that the diameter of the drawing 70 and cutting rollers is the same, and that the circumference is equal to the length of a stay plus the length of the piece of the strip that intervenes between two stays. The machine is so timed in practice as to sever the strip 75 half-way between two stays.

We have not shown any adjustments, for the reason that in practice each machine will be used upon a single length of stays. The machine may of course be made adjustable in any 80 simple and ordinary manner—for example, by removing the gears, the drawing and the cutting rollers, and substituting others in their places.

In order to avoid the possibility of the stays 85 becoming turned after being forced out by the fingers, we have provided a rest, 45, carried by a sleeve, 46, which reciprocates upon rod 47.

48 is a connecting-rod, one end of which is pivoted to sleeve 46, the other end being pivoted eccentrically to gear 32.

49 indicates stops secured to the bed-plate, against which the stays strike when forced out by the fingers, and which act to prevent them from being thrown too far or beyond the 95 strip. This portion of our invention is clearly illustrated in Figs. 4 and 5. As a stay is forced out, it strikes the stops and the forward end drops down upon the strip of covering material. The other end of the stay, however, is supported at an angle by rest 45, which reciprocates in a plane above the covering strip, so that the stay cannot possibly become turned. As the stay is carried forward, the rest moves with it until gear 32 has completed 100 a half-revolution. By this time the point of the stay will have passed into the folder and cannot have passed in otherwise than perfectly flat. The rest then returns to the position shown in Figs. 2 and 4, allowing the stay to 110 drop flat, and is then ready to receive the next stay.

In the modified form illustrated in Figs. 7 and 8 neither carrying-plate nor cross-slide is provided with recesses for the fingers. 115 The front of carrying-plate is provided with a concaved depression, 50, and the fingers are made of spring metal, ordinary stays being preferably used for this purpose. These fingers are held in position by a strip, 51, whose 120 surface conforms with depression 50, and which is held in position by screws 52. Any desired number of fingers may be used, and they may be adjusted or new ones may be substituted by simply loosening screws 52. It is of course desirable that the acting portion of the spring-fingers should lie flat upon the surface of the carrying-plate, as shown, leaving the other ends to project above the cross-slide. The action of 125 this form in use is precisely the same as the other.

The operation of the entire machine having been fully described in the description of the parts, further explanation will hardly be re-

quired. It will of course be understood that the details of construction may be widely varied without departing from the spirit of our invention.

5 We claim—

1. In a machine for covering stays, the magazine and reciprocating fingers for forcing the stays out singly, in combination with the folder, drawing-rollers, and a cutter.
- 10 2. The magazine having holes 19 and a slot, 21, and reciprocating fingers adapted to force the stays out singly through said slot, in combination with the folder, drawing-rollers, and cutting-rollers, as and for the purpose set forth.
- 15 3. In a machine for covering stays, the combination, with the magazine and reciprocating fingers for forcing the stays out singly, of rollers 11 and 12, which form the strip to receive the stays, the folder, drawing and pressing rollers 22 and 23, and rollers 26 and 27, one of which is provided with a cutter adapted to divide the strip between the stays.
- 20 4. In a machine for covering independent stays, the magazine and the reciprocating fingers for forcing the stays out singly, in combination with pasting-rollers, forming-rollers, a folder, and drawing and pressing rollers.
- 25 5. In a machine for covering corset-stays, the combination, with forming-rollers 11 and 12, a folder, drawing-rollers, and cutting-rollers, of a magazine having a slot at the back of just sufficient height to permit one stay to pass out, and holes 19 at the front, and reciprocating fingers which enter said holes, catch the lowermost stay, and force it through said slot and into the covering-strip.
- 30 6. In a machine for covering stays, the forming-rollers, drawing-rollers, cutting-rollers, and the folder, in combination with the magazine, a weight which holds the stays down flat, and reciprocating fingers which press them out singly into the covering-strip.

7. In a machine for covering stays, the combination, with the folder and drawing-rollers, of a magazine, the reciprocating fingers, and stops 49, as and for the purpose set forth.

8. The drawing-rollers and folder, in combination with the magazine, reciprocating fingers, stops 49, and a rest, 45, moving with the stay, whereby the latter is prevented from becoming turned.

9. The drawing-rollers, folder, magazine, and reciprocating fingers, in combination with rest 45, attached to sleeve 46, rod 47, by which said sleeve is carried, and a rod, 48, connecting said sleeve to one of the shafts.

10. In a machine for covering independent stays, the pasting, turning, and forming rollers, magazine, and reciprocating fingers, in combination with a folder, drawing-rollers, and a cutter.

11. The magazine and reciprocating fingers, in combination with trough 41, stops 49, rest 65 45, a folder, and the drawing-rollers.

12. The forming-rollers, stops, and moving rest 45, in combination with the magazine, reciprocating fingers, a folder, and the drawing-rollers.

13. In a machine for covering independent stays, drawing-rollers, cutting-rollers, a magazine, and trough 41, in combination with a cross-slide and fingers 17, bell-crank lever 34, and connecting-rod 35.

14. The drawing-rollers, folder, magazine, weight, and fingers, in combination with shaft 24, carrying gear 32, rod 47, sleeve 46, rest 45, and connecting-rod 48.

In testimony whereof we affix our signatures in presence of two witnesses.

WILLIAM A. NETTLETON.

CHARLES F. LITTLEJOHN.
